BUDOLF PLAÜELN, OF OFFENBACH-ON-THE-MAIN, GERMANY.

PROCESS FOR PRODUCTION OF LEAD ACETATE.

Application filed May 20, 1924. Serial No. 714,683.

Processes are known for the oxidation of metallic lead in acetic acid or a solution of lead acetate with air for the purpose of obtaining neutral or basic sugar of lead solutions (see Zeitschrift für angewandte Chemie, book 5, 3rd February, 1911, pages 209-210).

The practicability of the oxidation process referred to is dependent upon obtaining a continuous intimate contact of the air blown in between the total quantity of the lead threads on the one hand and the continual regular circulation of the solvent on the other hand. In the known processes a baking together of the lead masses occurs so that it is necessary to open out the air passages and to loosen the lead mass, which is often as hard as stone, within the boiler by manual labor at intervals of from two to three days, which can only be effected with difficulty whilst affecting the health of the workmen. It has now been found that by providing a regular vertical circulation of the liquid solvent it is possible to effect the quantitative oxidation of suitable quantities of lead by blowing in ordinary compressed air without the necessity of the extremely injurious breaking-up method and whilst excluding an excess pressure. It is even possible according to the invention to treat raw lead or lead ores containing antimony which could hitherto not be used and could only be oxidized with difficulty in the same manner and to the same practical extent as the very expensive twice-refined soft lead which has been used hitherto.

In the accompanying drawing is illustrated by way of example a suitable plant for carrying out the present process.

Figure 1 shows a sectional elevation and Figure 2 shows a cross section.

In a cylindrical chamber *a* of about seven meters in height and two meters in diameter there is mounted concentrically a lead container *b* which is preferably tapered upwardly and is open at the top and bottom. This container *b* is constructed of wood or sheet copper with the dimensions 6 x 1 meters. In the interior of this chamber *b* and at the bottom thereof there is arranged an air nozzle construction *c* arranged in the shape of a tripod, these nozzles being mounted on a perforated annular pipe which connects the various nozzle devices together. In

this lead container every second section is shortened at the bottom by 5 cm. At the upper end of the container there is provided directly below the level of the liquid or on the level of the liquid a band shaped perforated plate *e* which is about 10 cm. wide. The container is filled to substantially the top thereof with lead threads (10 to 12 tons).

The principle of the oxidation process is as follows:

Compressed air enters through the lateral pipe *d* into the tripod of nozzles *c* and flows through the column of lead. The saturated lead oxide solution formed in the interior of the chamber *b* by the rapid absorption of lead oxide is caused to pass through the perforated band by the action of the air into the solution contained in the outer chamber, and which is specifically lighter, and thus produces a continuous circulation.

The practical advantages of the invention are as follows:

1. By means of the above process 1.75 tons of metallic lead are converted into neutral or basic lead sugar within six to eight hours by the use of ten to twelve tons of lead for treatment. According to the known processes this result is obtained in eight to fifteen hours with the treatment of thirty to forty tons of lead.

2. This favourable result is obtained without excess pressure and the injurious breaking up of the lead masses by manual labor is eliminated.

3. By means of the above process it is possible to deal with the same rapidity with raw and scrap lead containing antimony and which is only oxidizable with difficulty in the same manner as the twice refined soft lead.

Having now particularly described and ascertained the nature of my said invention, and in what manner the same is to be performed, I declare that what I claim is:

1. The herein described method of producing lead acetates from metallic lead, consisting in placing lead in a liquid lead solvent of acetic acid character, and forcing compressed air upwardly through the mass of the lead and solvent, causing a continuous vertical circulation by means of the compressed air through the solvent.

2. The herein described method of pro-

ducing lead acetates from metallic lead, consisting in placing lead in a liquid lead solvent of acetic acid character, forcing compressed air upwardly through the mass of the lead and solvent, causing a continuous vertical circulation by means of the compressed air through the solvent and permit-

ting the oxidizing air which imparts circulation to the solvent to be discharged while being distributed over the cross sectional 10 area of the lead.

In witness whereof I affix my signature.

RUDOLF PLAÜELN.
